US0D1088550S

(12) **United States Design Patent** (10) **Patent No.:** **US D1,088,550 S**
(45) **Date of Patent:** **** Aug. 19, 2025**

(54) **RETRACTABLE STRAP HOUSING**

(71) Applicant: **MOUSESTRAP, LLC**, North Wilkesboro, NC (US)

(72) Inventor: **William F. Joyner**, North Wilkesboro, NC (US)

(73) Assignee: **MOUSESTRAP, LLC**, North Wilkesboro, NC (US)

(**) Term: **15 Years**

(21) Appl. No.: **29/868,585**

(22) Filed: **Dec. 7, 2022**

Related U.S. Application Data

(60) Continuation of application No. 17/138,511, filed on Dec. 30, 2020, now abandoned, which is a continuation of application No. 16/293,253, filed on Mar. 5, 2019, now Pat. No. 10,913,633, which is a division of application No. 15/630,504, filed on Jun. 22, 2017, now Pat. No. 10,233,052.
